UNITED STATES PATENT OFFICE

2,688,492

TRAVELING TOY ROCKING HORSE

Maurice D. Jacobs, Northport, N. Y.

Application August 24, 1951, Serial No. 243,476

9 Claims. (Cl. 280—1.175)

1

This invention relates to rocking devices, particularly advancing or travelling toy rocking horses, and has for its main object to provide a device of this character, which will have novel improved construction, and more efficient operation than is the case with similar devices proposed heretofore.

The present invention is an improvement on the travelling rocking horse for which Letters Patent of the United States have been issued to me on December 6, 1949; No. 2,490,059.

Another object of my invention is to provide a device of the type mentioned which may advance on shorter rearward and forward rocking than was the case with the earlier similar devices.

Still a further object of this invention is to provide a travelling or advancing rocking device, particularly a rocking horse, in which rear and front runners are provided with relative motion between them for causing the device to advance or travel and in which the front ends of the both, the rear and front runners will have identical bottom curvatures or rocking surfaces continued in different but tangentially meeting curvatures rearwardly whereby the transition of the rocking of the device from one runner to the other will be smooth and without shocks.

A further object of my invention is to provide identical registering rocking surfaces for the fronts of the front and rear runners whereby in the foremost rocking of the device, the rear runner will be adapted to carry the weight thereof and relieve the means connecting the two runners from the strain of such weight in such a position as is the case with the device of my said patent.

Still another object of this invention is to provide improved novel means to prevent a relative motion of the front and rear runners at the one side of the device while permitting relative motion at the other side, whereby the device upon rocking will also be caused to turn in the direction of its locked side.

Still further objects of my invention will be apparent as the specification of the same proceeds or will be pointed out therein.

In the drawings forming a part of this specification and accompanying the same:

Fig. 1 is an elevational view of a rocking horse built according to my invention, a portion of the same being broken away;

Fig. 2 is a plan view thereof;

Fig. 3 is a sectional view, the section being

2

taken on the line 3—3 of Fig. 2 and parts of the device having been removed;

Fig. 4 is a sectional detail on the line 4—4 of Fig. 3;

5 Figs. 5, 6 and 7 are sectional details of the left hand rocker device, the sections being taken on the respective lines in Fig. 1 and parts being removed;

10 Fig. 8 is a diagrammatic sectional view of one of the rockers of my device showing the relative position of the front and rear runners of which each rocker is composed, at slow forward rocking;

15 Fig. 9 is a diagrammatic fragmentary view indicating the position of the fronts of the runners when the device is in full forwardly rocked position and rests on the front part of the rear runner;

20 Fig. 10 is a similar view for rearward rocking after a quick release of the front runner. Dotted lines indicate position of front runner before release showing clearance between its rear portion and the floor.

25 Referring now to the drawings more in detail by characters of reference, the numeral 20 indicates my device, in general, being mainly composed of a right hand rocker, generally indicated by the numeral 21, a left hand rocker, generally indicated by the numeral 22, and the toy horse, generally indicated by the numeral 23. The two rockers are of identical construction, wherefore the description of one of them will suffice, and I now proceed to describe the construction of the left hand rocker 22.

30 The said rocker is composed of a rear runner, generally indicated by the numeral 24, and a front runner 25.

35 The rear runner 24 is a plate-like elongated member having a curved bottom 26 and a top 27, in the embodiment being shown as of the same curvature as the bottom. It also has right hand and left hand sides 28 and 29. In the embodiment shown the rear runner 24 is provided with a central slot 30 terminating considerably in front of its rear end 31, as indicated at 32. The rear end of said rear runner 24 is terminated with an upper inclined plane 33, and the front end thereof is also terminated in a similar inclined manner, as at 36. However, the space

40 or slot 30 therein is continued through to the front end, the same being open there and forming a fork like termination, generally indicated by the numeral 37, for the front end of the runner 24. Except for said open end 37, the top 45 of the rear runner is closed, as indicated at 38.

3

In the space or slot 30 of the rear runner is arranged the mentioned front runner, generally indicated by the numeral 25. This front runner is in the form of a plate 39 which is shorter and somewhat lower than the space 30 in the rear runner. It has an angular front formed by the sides 40 and 41, a curved top 42, a curved rear end 43, and a bottom 44, which is of the same curvature as the bottom 26 of the front of the rear runner 24. The two bottoms 26 and 44 of the rear and front runners are registering only through a part of their extent, as will be explained hereinafter. The rear runner 24 also is provided with a reduced or cut away portion 45 in the front part of its bottom 26.

Front and rear curved through-going slots 46 and 47 are arranged in the front runners, and pins 48 and 49 are secured in the rear runners carrying rollers 50 and 51 in the respective slots 46 and 47 whereby the front and rear runners may have a relative motion to one another through said rollers travelling in said slots, as will be obvious.

A resilient cord or band 52 is secured, at its rear end 53 on the front runner, and at its front end 54 on the rear runner, whereby the two runners are connected with said yielding but resilient member 52.

The resilient band 52 in the normal condition is short, as indicated in Figs. 1 and 10, whereby, normally, the front runner 25 is pulled forwardly with reference to the rear runner 24.

In the embodiment shown, the upper structure of my rocking device is in the form of a toy rocking horse 23, as has been mentioned, and to support the same, front and rear cross members 55 and 56 are secured to the respective rockers 21 and 22, thereby forming a rigid structure of these parts. The toy horse 23 will have a body proper and seat, or saddle, member 57, a head 58 and front and rear legs 59 and 60.

As will be seen, the toy horse 23 rests by its legs on the respective cross members 55 and 56.

Grips 61 project from the head 58 whereby the child using the seat 57 may have a grip on the head. The head 58 is secured on and is rotatable with shaft 62, the construction and purpose of which will be more fully explained hereinafter.

In Figs. 1 and 2 the device is shown in its position as it is rocking forwardly, after its rearward rocking, and is arriving to a phase of the forward rocking when the support thereof is changing from the rear runners to the front runners.

The operation of my present rocking device is similar to the one described in my said patent for a travelling rocking horse.

When the user is rocking the device slowly forwardly as shown in Fig. 8 (arrow 24a), the same will entirely rest for the latter part of said movement on the forward runners, as indicated at 63, since the cut out portions 45 of the rear runners 24 will prevent a frictional engagement of the rear runners, at the said phase of the forward rocking of the device, with the ground or floor 64. In such a forward rocking the device will frictionally rest on the front runners 25 and will fix the same in this position, on the floor, while the rear runners 24 will slide forwardly with reference to the front runners, under the weight of the upper structure 23 and the person occupying the same, as indicated by the arrow 65. During such a motion, the rear runner will advance forwardly with reference to the front runner and the resilient band 52 between the two runners will be stretched as shown in Fig. 8.

4

Upon still further forward rocking the bottom surface 26 of the rear runner will engage the floor and for a short while the front runner will be released and the band 52 will pull it somewhat forwardly, while at the final phase of the forward rocking both runners will grip the floor, as indicated in the fragmentary section of Fig. 9. The former position of the front runner is indicated in dotted lines.

It is to be noted that from a point 65, about at the end of the cut out part or recess 45, the rear portion of the bottom 26 of the rear runner will have a somewhat larger diameter for its curvature 65a than is the diameter for the front part thereof, which as has been mentioned is the curvature of the bottom of the front runner all of its length. The larger curvature 65a of the rear portion of the rear runner of course will be a tangential continuation of the smaller curvature of the front thereof, so that the rear runner may continue either forward or rearward rocking over this point, switching from one curve to the other very smoothly without any shock.

Now, after the most forward position, as indicated in Fig. 9, the rear runner starts to rock in a reverse direction, rearwardly, as indicated by the arrows 24b in Figs. 9 and 10.

For a period of time both runners 24 and 25 will engage the floor 64 and their relative position will not change. However, when the rear runner arrives to the point 65 it will continue to run on the larger rear curve 65a and the front runner will be released, having a smaller curvature, as indicated at 26a.

The resilient band 52 now very quickly will pull the front runner into its foremost position.

Such a phase of the rearward rocking of the device is illustrated in Fig. 10.

The device continues its rearward rocking on the rear runner 24 and then will again rock forwardly until it arrives to the position of Fig. 8 when for a time it again will rest on the front runner 25 and the rear runner again will slide forwardly, as has been described hereinbefore.

It will be seen that upon a rearward rocking the front runner will advance, and upon a forward rocking the rear runner will slide forwardly, and my rocking horse, aside of rocking back and forth, will also travel as has been described in my said patent.

However, on account of the rear portion of the front runner having smaller curvature than the rear part of the rear runner, the release of the front runners will be quicker and earlier than was the case with the device of said patent and a full measure of advance will be assured in any rocking of the present invention.

A rubber limiting member 68 is secured across the front end of the space 30 in the rear runner and the front runner will strike it when arriving to its foremost position (Fig. 10).

The present device will be adapted to perform a certain amount of forward or advancing movement or travel even with less forward and rearward rocking as was the case with the device of my said patent, and also on a quick rocking, as will be obvious.

Another great improvement of the present device over the rocking horse of my said patent lies in the fact that the front portion of both, the rear and front runners, will have the same registering bottom curvatures or rocking surfaces, whereby in the extreme forward rocking of the device, the rear runner will be locked and the weight of the device will rest thereon and on

the ground, instead of on the pins and rollers in the slots 46 and 47, as is the case with the device of said patent.

This arrangement, obviously, will relieve the pins and rollers of the weight at such phases of the operation of the device and will insure a smoother operation and longer life for my rocking device.

Finally, at the foremost rocking of the device the bottom curvatures or rocking surfaces of the front and rear runners will be the same and will register and the device will then change from one runner to the other very smoothly. This action will be similar on the rearward rocking when changing the weight of the device from the front runners to the rear runners whereby the rocking of the device in both directions and the changing from one runner to the other will be effected without any shocks and in the very simple smooth continuous manner as against the shocks produced in the device of said patent.

As has been mentioned, the head 58 of the horse 23 will be separated from the body 57 thereof and will be secured on a shaft 62 rotatable in said body. The lower end of the shaft is bent forwardly, as indicated at 71 (Figs. 1 and 3) and will engage a ring 72 which is secured on a transversely slideable bar 73, as by the screw 74. Bar 73 is slideable in an appropriate slot 75 in the forward cross member 55.

The rear runner 24 of the right hand rocker member 21 will have an aperture 76 provided in its inner leg 29 and a similar aperture 77 will be provided in the inner leg 29 of the rear runner 24 of the left hand rocker member 22. Upon a right hand turning of the head 58, and with it the shaft 62, the sliding bar 73 will be pushed through the left hand aperture 77 until it will strike the respective front runner 25 whereby the left hand front and rear runners will be prevented from a relative sliding motion against one another and that side of the device will act like an ordinary rocking device with a fixed rocker while the other side will remain advancing and therefore the device will turn to the right. Similarly, if the head of the horse will be turned in a left hand direction, the whole device will turn in the same manner, therefore the rocking horse will be caused to turn right or left as the horse's head is turned in the respective directions, and this result will be attained with the very simple construction of the shaft 62, ring 72 and sliding bar 73 as described.

On account of the said quick release of the front runners, their advance will be quicker than was the case with the device of said patent and the rocking horse of the present construction will turn quicker and with larger amounts.

Having thus described my invention in some detail, what I claim as new and desire to protect by Letters Patent of the United States, is:

1. In an advancing rocking device, a rear runner, a front runner thereon shorter than said rear runner, means to provide relative predetermined forward motions between the two runners, said two runners having identical bottom curvatures, or rocking surfaces, at their front ends, but with the bottom of the rear runner being recessed along the bottom surface for a distance shorter than the length of the front runner to allow the front runner to become the bearing surface during a phase of the rocking motion, the rear of the rear runner then having a larger curvature for its rear rocking surface whereby in the foremost position of the runners each will engage the

ground, then for the aforesaid phase of its rocking the device may entirely be supported by the front runners, and then again for a period by the rear runners only, the transition from one runner to the other being quickly and easily executed through said smaller curvature in the rear part of the front runner than the curvature in the rear part of the rear runner.

2. In a device of claim 1, a limiting member for the forward motion of the front runner at the front end of the rear runner.

3. In a device, as set forth in claim 1, said two curvatures in said rear runner meeting in a smoothly continuous tangential manner, and said curvature of the front runner also meeting the curvatures in the rear runner in a similar manner, whereby the transit from one curvature to the other will be smooth and without any shock.

4. In a device of claim 1, said front curvature of the rear runner being continued in a continuous unbroken manner to the front end of said runner.

5. In an advancing rocking device, having a pair of front and rear runners at each side thereof, a horse shaped connecting body structure carried by said rear runners, and the advancing being provided by the relative motion of the two runners, a vertical shaft rotatable in said horse shaped connecting structure and having rotating means in the shape of the head of a horse secured thereon and rotatable therewith, a sliding transverse bar in the device below the front of said horse shaped connecting structure, a ring secured on said bar, the lower end of said shaft being bent and passed through said ring, said front runners being in a space inside of said rear runners, an aperture in each rear runner adapted to permit the respective end of said bar to pass therethrough when the said rotating means and the shaft is turned in the respective direction correspondingly moving said bar, said bar then preventing a relative motion of the respective front runner, but permitting an advancing of the other front runner and thereby causing the horse to turn in said direction when rocking.

6. In an advancing rocking device, the combination comprising a pair of rear runners, a connecting body structure carried by said rear runners, a pair of front runners, said front runners being in a space inside said rear runners, means to provide a relative predetermined forward motion between each front runner and each rear runner, said front runners and said rear runners having identical bottom curvatures, or rocking surfaces, at their front ends, but with the bottom of the rear runner being recessed along the bottom surface for a distance shorter than the length of the front runner to allow the front runner to become the bearing surface during a phase of the rocking motion, the rear of the rear runners then having larger curvatures for their rear rocking surfaces whereby in the foremost position of said runners each will engage the ground, then for the aforesaid phase of its rocking the device may entirely be supported by the front runners only, the transition from one pair of runners to the other pair being quickly and easily executed through said smaller curvature in the rear part of the front runners than the curvature in the rear part of the rear runner, normally disengaged engaging means for preventing a relative motion of one front runner but permitting an advancing of the other front runner and thereby causing the device to turn in said direction when rocking.

7. In an advancing rocking device, the combination comprising a pair of rear runners at each side thereof, a connecting body structure carried by said rear runners, a pair of front runners at each side thereof, said front runners being in a space inside said rear runners, means to provide relative predetermined forward motion between each front runner and each rear runner, said front runners and said rear runners having identical bottom curvatures, or rocking surfaces, at their front ends, but with the bottom of the rear runner being recessed along the bottom surface for a distance shorter than the length of the front runner to allow the front runner to become the bearing surface during a phase of the rocking motion, the rear of the rear runners then having larger curvatures for their rear rocking surfaces whereby in the foremost position of said runners each will engage the ground, then for the aforesaid phase of its rocking the device may entirely be supported by the front runners, and then again by the rear runners only, the transition from one pair of runners to the other pair being quickly and clearly executed through said smaller curvature in the rear part of the front runners than the curvature in the rear part of the rear runners, a vertical shaft rotatable in said body structure, rotating means secured thereon and rotatable therewith, a slidable transverse bar below the front of said connecting structure, a 30 ring secured on said bar, the lower end of said shaft being bent and passed through said ring, an aperture in each rear runner adapted to permit the respective end of said bar to pass therethrough when said rotating means and said shaft 35 is turned in the respective direction correspondingly moving said bar, said bar then preventing a relative motion of the respective front runner but permitting an advancing of the other front runner and thereby causing said rocking device 40 to turn in said direction when rocking.

8. In a device, as set forth in claim 7, a connecting body structure carried by said rear runners of such shape, contours, and dimensions as to simulate the body of a horse and rotating means secured on said vertical shaft and rotatable therewith of such shape, contours, and dimensions as to simulate the head of a horse.

9. In an advancing rocking device, having a pair of front and rear runners on each side thereof, a connecting body structure carried by said rear runners, and the advancing being provided by the relative motion of the two runners; a vertical shaft rotatable in said body structure, rotating means secured thereon and rotatable therewith, a slidable transverse bar below the front of said connecting body structure, a ring secured on said bar, the lower end of said shaft being bent and passed through said ring, an aperture in each rear runner adapted to permit the respective end of said bar to pass therethrough when said rotating means and said shaft is turned in the respective direction correspondingly moving said bar, said bar then preventing a relative motion of the respective front runner, but permitting an advancing of the other front runner and thereby causing the rocking device to turn in said direction when rocking.
